BRAUN TUBE

Manfred von Ardenne, Berlin, Germany

Application April 17, 1933, Serial No. 666,555
In Germany March 27, 1931

17 Claims. (Cl. 250—27.5)

The invention relates to a reception device for television with Braun tubes.

Improvements in the quality of the image in the case of television receiving arrangements employing Braun tubes operating with deflection control are obtained by the use of after-concentration cylinders.

However, as extensive investigations have shown, a certain distortion of the image is also caused by these improved Braun tubes.

Now the further object of the invention is by an arrangement, in which all distortions are wholly eliminated. By reason of the deflecting plate, or pairs of deflecting plates, the cathode ray is imparted a direction, which deviates from the central one, and which could also not be entirely compensated by the after-concentration cylinder. It was certainly possible with the assistance of the after-concentration cylinder to obtain a considerable improvement in the image, but this, as later experiments have shown, is based solely on the fact that the ray, which is caused to diverge, particularly by reason of the deflection, is again more sharply concentrated, whereby certainly a partial return to the center line is also obtained.

According now to the invention, there is employed for returning the ray to the axis of the tube a second deflecting plate, or pair of deflecting plates, which preferably operate in counter-cadence to the deflecting plate controlling the intensity of light. By reason of this counter-plate principle it is accomplished that the ray after leaving the vicinity of the second plate of the returning plate proceeds co-axially to the tube, so that in this case an after-concentration cylinder is not absolutely essential. This arrangement will be described more fully in conjunction with a possible form of embodiment as illustrated in the appended drawing, the single figure of which shows a Braun tube and certain connecting means associated therewith, both designed in accordance with this invention.

In the figure 56 is the cathode, 57 the Wehnelt cylinder, 58 the deflecting plate controlling the intensity of the ray, and 59 the anode. The deflecting plate 5 again returns the ray to the center axis of the tube, where the same, if necessary, may again be more greatly concentrated by an after-concentration cylinder 61 and thereupon deflected by means of the deflecting plates systems 62 and 63 in two directions for scanning the fluorescent screen 64 on which the image to be transmitted appears.

According to the additional subject matter of

the invention, the distance of the deflecting plate 58 and also that of the returning plate 5 from the axis of the tube is so chosen that the same is large as compared with the diameter of the ray at the point of control, in order to avoid distortions. These distortions are based to a large extent on the space charge fog which develops between this plate and the ray, and which prevents a linear control characteristic.

Since the influence of the two deflecting and returning plates, or pairs of plates, on the cathode ray varies in consequence of the varied speed of the electrons arising from the intermediately located anode, the D. C. potential bias of the returning plate 5 is adjusted separately from that of the plate 58. For the purpose of dynamic control the two plates 58 and 5 may be connected in simple fashion by means of a condenser 72. The suitable biasing potential for the plate 5 may be obtained in simple manner by connecting this with the anode 59 through the medium of a regulable resistance 71.

Although, as stated above, it is not absolutely essential to employ the after-concentration cylinder 61 when making use of the counter-plate principle, the combination of after-concentration cylinder and counter-plate principle nevertheless results in very considerable improvements in the quality of the image, as it is possible to eliminate not only the image-point displacement by the plate 5 but also the lack of sharpness by the after-concentration cylinder 61.

In order to also obtain from a dynamic standpoint a particularly fine adjustment of the co-axial nature of the ray, there is provided, according to the invention, outside of the tube a displaceable plate 66, which is situated parallel to the returning plate 5 and is connected with the same. The displacement of this plate may be performed in desired direction, and permits of extremely fine subsequent adjustment of the return deflection of the ray. This plate is connected with the returning plate.

As shown in the single figure of the drawing, further plates 67, 69, and 70, hereinafter termed "counter-plates", may be provided so that pairs of plates are formed, one comprising the plates 58 and 67, another one comprising the plates 5 and 69, and a third one comprising the plates 66 and 70, the relative positions of the two plates of each of the mentioned pairs being symmetrical with respect to the tube axis. By using such pairs instead of the single plates 58, 5 or 66 respectively, the homogeneity of the deflecting fields is increased, the effect of which improvement is

particularly favourable as regards the counter plate 70 of the plate 66. This last mentioned counter plate is preferably earthed with respect to alternating current, but supplied with a D. C. 5 potential for the purpose of preventing a change in the speed of the cathode ray.

To preclude detrimental influence on the part of the controlling plates 58 and 5 on the concentration cylinders 57 and 61 the distance between 10 the initial-deflection plates, or pairs of plates and the concentration cylinders is, according to 15 the invention, made of sufficient extent. The complete control of the television arrangement as described occurs in the known manner by 15 passing the light intensity potential to the initial-deflection plate 58 and the image or line potential to the pairs of plates 62 and 63.

I claim:

1. A Braun tube comprising a cathode, deflecting means and a fluorescent screen, a concentrating cylinder arranged near said cathode, one deflecting plate arranged at one side of the tube-axis, a perforated shutter mounted between said deflecting plate and said screen, a further 25 deflecting plate arranged at the opposite side of the tube axis, an adjustable deflecting plate arranged outside said tube in parallel to said further deflecting plate and connected thereto, and a concentrating cylinder arranged between 30 said further deflecting plate and said deflecting means.

2. A Braun tube comprising a cathode, a perforated anode and a fluorescent screen, means for deflecting the cathode ray in one direction 35 and means for deflecting the ray in a direction perpendicular to the first said one for scanning said screen, said deflecting means being arranged between said anode and said screen, one deflecting plate arranged at one side of the tube 40 axis between said cathode and said anode, said deflecting plate being adapted to be supplied with a control voltage, and a further deflecting plate arranged at the opposite side of the tube axis between said anode and said deflecting 45 means, said further deflecting plate being adapted to be supplied with a redeflecting voltage.

3. A Braun tube comprising a cathode, a perforated anode and a fluorescent screen, means for deflecting the cathode ray in one direction 50 and means for deflecting the ray in a direction perpendicular to the first said one for scanning said screen, said deflecting means being arranged between said anode and said screen, one deflecting plate arranged at one side of the tube axis 55 between said cathode and said anode, said deflecting plate being adapted to be supplied with a control voltage, a further deflecting plate arranged at the opposite side of the tube axis between said anode and said deflecting means, said 60 further deflecting plate being adapted to be supplied with a redeflecting voltage, and concentrating means arranged between said further deflecting plate and said deflecting means.

4. A Braun tube comprising a cathode, a perforated anode and a fluorescent screen, means for deflecting the cathode ray in one direction 65 and means for deflecting the ray in a direction perpendicular to the first said one for scanning said screen, said deflecting means being arranged between said anode and said screen, one deflecting plate arranged at one side of the tube axis 70 between said cathode and said anode, said deflecting plate being adapted to be supplied with a control voltage, a further deflecting plate 75

arranged at the opposite side of the tube axis between said anode and said deflecting means, said further deflecting plate being adapted to be supplied with a redeflecting voltage, and a concentrating cylinder arranged between said further deflecting plate and said deflecting means.

5. A Braun tube comprising a cathode, a perforated anode and a fluorescent screen, means for deflecting the cathode ray in one direction and 10 means for deflecting the ray in a direction perpendicular to the first said one for scanning said screen, said deflecting means being arranged between said anode and said screen, one deflecting plate arranged at one side of the tube axis between said cathode and said anode, said deflecting plate being adapted to be supplied with a control voltage, and a further deflecting plate arranged at the opposite side of the tube axis between said anode and said deflecting means, said further deflecting plate being adapted to be supplied with a redeflecting voltage comprising a 15 variable direct current bias.

6. A Braun tube comprising a cathode, a perforated anode and a fluorescent screen, means for deflecting the cathode ray in one direction and 20 means for deflecting the ray in a direction perpendicular to the first said one for scanning said screen, said deflecting means being arranged between said anode and said screen, one deflecting plate arranged at one side of the tube axis between said cathode and said anode, said deflecting plate being adapted to be supplied with a control voltage, a further deflecting plate arranged at the opposite side of the tube axis between said anode and said deflecting means, said further deflecting plate being adapted to be supplied with a redeflecting voltage, and a variable 25 resistance connecting said further deflecting plate with said anode.

7. A Braun tube comprising a cathode, a perforated anode and a fluorescent screen, means for deflecting the cathode ray in one direction and 30 means for deflecting the ray in a direction perpendicular to the first said one for scanning said screen, said deflecting means being arranged between said anode and said screen, one deflecting plate arranged at one side of the tube axis between said cathode and said anode, said deflecting plate being adapted to be supplied with a control voltage, a further deflecting plate arranged at the opposite side of the tube axis between said anode and said deflecting means, and 35 connecting means comprising a condenser connecting the two said deflecting plates.

8. A Braun tube comprising an envelope, a cathode, a perforated anode and a fluorescent screen, means for deflecting the cathode ray in one direction and means for deflecting the ray in a direction perpendicular to the first said one for scanning 40 said screen, said deflecting means being arranged between said anode and said screen, one deflecting plate arranged at one side of the tube axis between said cathode and said anode, said deflecting plate being adapted to be supplied with a control voltage, a further deflecting plate arranged at the opposite side of the tube axis between said anode and said deflecting means, said further deflecting plate being adapted to be supplied with a redeflecting 45 voltage, and a third deflecting plate movably mounted outside said envelope and also adapted to be supplied with a redeflecting voltage for fine adjustment of the redeflection.

9. A Braun tube comprising a cathode, a per-

forated anode and a fluorescent screen, means for deflecting the cathode ray in one direction and means for deflecting the ray in a direction perpendicular to the first said one for scanning said screen, said deflecting means being arranged between said anode and said screen, one pair of deflecting plates arranged between said anode and said cathode, said pair of deflecting plates being adapted to be supplied with a control voltage, and a further pair of deflecting plates arranged between said anode and said deflecting means, said further pair of deflecting plates being adapted to be supplied with a redeflecting voltage.

15. 10. A Braun tube comprising a cathode, a perforated anode and a fluorescent screen, means for deflecting the cathode ray in one direction and means for deflecting the ray in a direction perpendicular to the first said one, for scanning said screen, said deflecting means being arranged between said anode and said screen, one pair of deflecting plates arranged between said cathode and said anode, said pair of deflecting plates being adapted to be supplied with a control voltage, a further pair of deflecting plates arranged between said anode and said deflecting means, said further pair of deflecting plates being adapted to be supplied with a redeflecting voltage, and concentrating means arranged between said further pair of deflecting plates and said deflecting means.

11. A Braun tube comprising a cathode, a perforated anode and a fluorescent screen, means for deflecting the cathode ray in one direction and means for deflecting the ray in a direction perpendicular to the first said one for scanning said screen, said deflecting means being arranged between said anode and said screen, one pair of deflecting plates arranged between said cathode and said anode, said pair of deflecting plates being adapted to be supplied with a control voltage, a further pair of deflecting plates arranged between said anode and said deflecting means, said further pair of deflecting plates being adapted to be supplied with a redeflecting voltage, and a concentrating cylinder arranged between said further pair of deflecting plates and said deflecting means.

12. A Braun tube comprising a cathode, a perforated anode and a fluorescent screen, means for deflecting the cathode ray in one direction and means for deflecting the ray in a direction perpendicular to the first said one for scanning said screen, said deflecting means being arranged between said anode and said screen, one pair of deflecting plates arranged between said cathode and said anode, said pair of deflecting plates being adapted to be supplied with a control voltage, and a further pair of deflecting plates arranged between said anode and said deflecting means, said further pair of deflecting plates being adapted to be supplied with a redeflecting voltage comprising a variable direct current bias.

13. A Braun tube comprising a cathode, a perforated anode and a fluorescent screen, means for deflecting the cathode ray in one direction and means for deflecting the ray in a direction perpendicular to the first said one for scanning said screen, said deflecting means being arranged between said anode and said screen, one pair of deflecting plates arranged between said cathode and said anode, said pair of deflecting plates being adapted to be supplied with a control voltage, a further pair of deflecting plates arranged be-

tween said anode and said deflecting means, said further pair of deflecting plates being adapted to be supplied with a redeflecting voltage, and a variable resistance connecting said further pair of deflecting plates with said anode.

14. A Braun tube comprising a cathode, a perforated anode and a fluorescent screen, means for deflecting the cathode ray in one direction and means for deflecting the ray in a direction perpendicular to the first said one for scanning said screen, said deflecting means being arranged between said anode and said screen, one pair of deflecting plates arranged between said cathode and said anode, said pair of deflecting plates being adapted to be supplied with a control voltage, a further pair of deflecting plates arranged between said anode and said deflecting means, and connecting means comprising a condenser connecting the two said pairs of deflecting plates.

15. A Braun tube comprising an envelope, a cathode, a perforated anode and a fluorescent screen, means for deflecting the cathode ray in one direction and means for deflecting the ray in a direction perpendicular to the first said one for scanning said screen, said deflecting means being arranged between said anode and said screen, one pair of deflecting plates arranged between said cathode and said anode, said pair of deflecting plates being adapted to be supplied with a control voltage, a further pair of deflecting plates arranged between said anode and said deflecting means, said further pair of deflecting plates being adapted to be supplied with a redeflecting voltage, and a third pair of deflecting plates movably mounted outside said envelope and also adapted to be supplied with a redeflecting voltage for fine adjustment of the redeflection.

16. A Braun tube comprising a cathode, an anode, a picture receiving screen, said anode being mounted between said cathode and said screen, electrodes for deflecting the cathode ray in one direction and means for deflecting the cathode ray in a direction perpendicular to the first said one for scanning said screen, said electrodes and said means for deflecting the cathode ray being mounted between said anode and said screen, an electrode for concentrating the cathode ray mounted near said cathode, means for further concentrating the cathode ray comprising an electrode mounted between said anode and said deflecting electrodes, said electrode mounted between said anode and said deflecting electrodes being spaced far enough from said deflecting electrodes for avoiding a disturbing influence upon one another.

17. A Braun tube comprising a cathode, an anode, a picture receiving screen, said anode being mounted between said cathode and said screen, electrodes for deflecting the cathode ray in one direction and means for deflecting the cathode ray in a direction perpendicular to the first said one for scanning said screen, said electrodes and said means for deflecting the cathode ray being mounted between said anode and said screen, an electrode for concentrating the cathode ray mounted near said cathode, means for further concentrating the cathode ray comprising a cylindrical electrode mounted between said anode and said deflecting electrodes, said cylindrical electrode being spaced far enough from said deflecting electrodes for avoiding a disturbing influence upon one another.

MANFRED VON ARDENNE.
